UNITED STATES PATENT OFFICE.

WILLIAM J. LUTTON, OF PATERSON, NEW JERSEY.

LET-OFF MECHANISM FOR LOOMS.

1,105,335.

Specification of Letters Patent. Patented July 28, 1914.

Application filed December 19, 1911. Serial No. 666,793.

To all whom it may concern:

Be it known that I, WILLIAM J. LUTTON, a citizen of the United States, and resident of Paterson, in the county of Passaic and State of New Jersey, have invented a new and useful Let-Off Mechanism for Looms, of which the following is a specification.

My invention relates to let-off mechanism for looms, with the object in view of providing means for automatically maintaining a uniform stress on the warp threads as they are let off step by step from the warp beam.

In the accompanying drawings, Figure 1 is a vertical section, partly in side elevation, in the plane of the line A—A, Fig. 2, of so much of a loom as will suffice to show the practical application of my invention. Fig. 2 is an end view broken away through the center, Fig. 3 is an enlarged partial horizontal section in the plane of the line B—B, Fig. 1, Fig. 4 is an enlarged partial vertical section in the plane in which Fig. 1 is taken, showing in full lines the position which the parts assume when the warp beam is about to be released to let off warp, and in dotted lines the position in which the trip bar is held while the pawl which releases the warp beam is operated, Fig. 5 is a view in detail in elevation showing the weight retaining device in operative position, Fig. 6 is a view of the same in vertical section, Fig. 7 is a view taken in a plane corresponding to that in which Fig. 1 is taken and showing a modification of certain parts, Fig. 8 is a partial horizontal view in the plane of the line C—C of Fig. 7, and Fig. 9 is an enlarged view in detail, in side elevation, showing the action of the modified mechanism for lifting and maintaining the trip bar in raised position while the pawl releases the warp beam.

The loom frame is denoted by 1 and may be of any well known or approved construction. The vibrating arm for operating the lay is denoted by 2, the crank shaft for transmitting motion to it by 3, and the link connecting the crank shaft with the arm by 4. The warp beam, denoted by 5, is mounted on a shaft 6, supported in suitable bearings 7 carried by the bracket frame 8 fixed to the loom frame 1. Fixed to rotate with the warp beam is a brake drum 9 and a ratchet toothed wheel, 10. A band brake 11 is secured at one end to the frame 8 at 12 and after passing around the brake drum 9, the opposite end of the brake is attached to a bolt 13, the threaded end of which extends

through a hole in a stud 14 projecting from the frame 8 and is provided with a wing nut 15 for tightening the brake 11 on the drum 9 at pleasure.

A warp guide roller 16 is mounted on a shaft 17 carried by uprights 18, 19, fixed to the frame 8, and a weighted floating roller 20 is suspended by the warp threads in their passage from the warp beam 5 to the guide roller 16. The floating spindle 21 on which the floating roller 20 turns is provided with depending links 22, 23, which support a bar 24 on which a series of weights 25 are threaded, the number of weights depending upon the stress which it is desired to place upon the warp threads. The links 22, 23, are provided with loops 26, 27, which embrace the bar 24, and the opposite ends of the bar are projected through elongated vertical slots 28, 29, in standards 30, 31, preferably extending from the floor up to the lower part of the frame 8, to which they are secured. The ends of the bar 24, which project through the said elongated slots, are conveniently held in the slots by cotter pins 32, 33, while they are fitted to slide freely up and down within the slots. Either end of the bar 24 may be withdrawn from the slot by removing the cotter and sliding the bar 24 endwise through the suspension loops 26, 27, and through the opposite slot, whenever it is desired to remove or add one or more weights.

The weight bar with weights thereon may be sustained at any time in the desired elevated position, independently of the warp threads by means of blocks 34, 35, provided with bolts 36 (see Fig. 6) which extend through the slots 28, 29, and have tail nuts 37, engaged therewith and with the standards on the opposite sides of the slots, whereby the blocks may be slid upward into touch with the bar 24 or to such a height as it may be desired to sustain the bar, and then locked to the standards by screwing up the tail nuts.

The warp beam is held against unintentional rotation by a pawl 38, pivoted to the frame 8 at 39, the tail of the pawl extending downwardly a considerable distance and having connected therewith a spring 40 for holding it in engagement with the ratchet toothed wheel 10. The pawl 38 is released from the wheel 10 and the warp beam allowed to rotate a step by the rise of the floating roller 20 and its weight as the warp threads 41 are

gradually taken up by the weaving. This is accomplished as follows: A reciprocating rod or bar 42 is connected at one end with the vibrating arm 2 and at its opposite end 5 carries a folding finger 43. The finger 43 is pivoted at its upper end to the rod or bar 42 and its lower end rests lightly on or is located in proximity to a shelf 44 along which the said finger slides back and forth as the 10 bar 42 is reciprocated. The weight of the finger end of the bar 42 is for the most part or entirely taken by a bracket 45 on the tail of the pawl 38 (see Fig. 3). The finger 43 is caused to assume a folded position, as 15 shown in Fig. 1, by a spring 46 connected at one end to the bar 42 and at its opposite end to the finger 43 by means of a bent connecting rod 47. A stop 48 on the bar 42 limits the folding movement of the finger, 20 holding it, when in its folded adjustment, preferably at an angle of about 45° to the bar 42.

Attached to the weight bar 24 is a catch 49, in the present instance an L-shaped catch, 25 the end of which is in position to rise in close proximity to the outer end of the shelf 44 as the floating roller 20 and its weight rise, so that when the end of the catch projects above the end of the shelf, as shown 30 in Fig. 4, the end of the finger 43, as the bar 42 moves to the right, as the drawing is held, will engage the catch and be rocked into a position at right angles to the bar 42, as shown in full lines, Fig. 4, thereby lifting 35 the bar 42 so that a lateral projection 50 thereon will ride up an incline 51, as the bar 42 moves in the opposite direction, raising the bar into the position shown in dotted lines, Fig. 4, and maintaining it in a raised 40 position until a projection 52 on the bar has engaged the tail of the pawl 38 and tripped the pawl. As soon as this has been accomplished, and the floating roller 20 and its weight allowed to drop by the turning of 45 the warp beam, the projection 50 will drop through a recess 53 in the edge of the incline permitting the bar 42 to drop onto the bracket 45 with its finger 43 folded and in 50 position to again operate the bar when the catch 49 shall again rise into position to engage it.

As the bar 42 is thrown upward by the finger 43 on its stroke to the right to lift the projection 50 into position to ride up the 55 incline 51, the possible engagement of the projection 50 with the incline on this stroke is provided for by mounting the incline in rocking adjustment on a standard 54 attached to the frame 1, the said incline being held in normal position by a spring 55 which permits the incline to tilt to allow the projection 50 to pass. A stop 56 prevents the incline from tilting in the opposite direction.

65 In the modified form shown in Figs. 7

to 9 inclusive the incline for lifting the pawl tripping bar is fixed in position and the projection on the bar is yieldingly connected with the bar. In this form too, the bar raising finger is dispensed with and the bar 70 is supported by a bracket secured to the frame 1. The modified pawl tripping bar is denoted by 57, its supporting bracket by 58, and the projection carried thereby for engaging the tail of the pawl by 52, as this, 75 in form and position, is the same as has heretofore been explained, and until the bar 57 is lifted reciprocates in and out of a recess 59 in the tail of the pawl 38. The incline is denoted by 60 and is fixed at one 80 end to the frame 1 and supported by the standard 61. The incline has a recess 62 in its edge for allowing the bar raising projection to drop through. The bar raising projection is denoted by 63 and is on a 85 tilting piece 64 pivoted to an upward extension 65 on the bar 57 and held yieldingly against a stop 66 by a spring 67. A stop 68 limits the tilt of the piece 64. The free end of the bar 57 lies in the path of the 90 weight bar 24 and as the latter rises it gradually lifts the bar 57 until the projection 63 reaches a height where it will ride up the incline 60 and thereby raise the projection 52 above the recess 59 and cause it 95 to engage the tail of the pawl and trip it.

In operation, the warp beam having by its brake band been placed under such restraint as found desirable for letting off the warp when released, and the desired tension having been applied by giving the floating roller 20 the necessary weight, the weaving will gradually lift the floating roller and its weight as the warp is taken up, until the bar 42 or 57 is lifted by the action of 10 the rising weight bar bringing the inclined plane into action to further lift and maintain lifted for a short period of time the said bar to cause its projection 52 to engage the tail of the pawl 38 above the recess 59 11 and thereby trip the pawl and allow the warp beam to rotate a step to let off warp.

It will be observed that at no time is the tension on the warp varied as the weighted roller 20 is resting thereon both when the 11 warp beam is held against rotation and when it is allowed to rotate and furthermore, any stretching of the threads may take place without in any degree varying the tension.

What I claim is:—

1. In a loom, a warp beam, a pawl and ratchet for holding the warp beam against rotation, a floating roller for applying stress to the warp threads, a reciprocating bar having its free end in position to be lifted during the rise of the floating roller, and means adapted to coact with the reciprocating bar to cause it to rise during the rise of the floating roller, the said reciprocating 11

bar being provided with means for engaging and tripping the pawl when the floating roller reaches a predetermined height.

2. In a loom, a warp beam, a ratchet and pawl for holding the warp beam against rotation, a weighted roller for applying stress to the warp threads, a reciprocating bar provided with a projection in position to engage and trip the pawl when the bar reaches a predetermined height, a folding finger pivoted to the reciprocating bar and means connected with the weighted roller for engaging the finger and causing it to unfold and lift the reciprocating bar when the floating roller reaches a predetermined height.

3. In a loom, a warp beam, a ratchet wheel and pawl for holding the warp beam against rotation, a weighted roller for applying stress to the warp threads, a catch connected to rise and fall with the weighted roller, a reciprocating bar provided with a projection for engaging and tripping the pawl, and a spring actuated finger pivoted to the reciprocating bar and adapted to engage the said catch when the latter reaches a predetermined height whereby the reciprocating bar may be lifted and the pawl tripped.

4. In a loom, a warp beam, a pawl and ratchet for holding the warp beam against rotation, a floating weighted roller for applying stress to the warp threads, a reciprocating bar, means coöperating therewith to lift the bar when the weighted floating roller reaches a predetermined height, the said bar being provided with a projection in position to engage and trip the pawl, an inclined plane and a projection carried by the bar in position to ride up the inclined plane when the bar is lifted and thereby further lift and hold the bar momentarily raised.

5. In a loom, a warp beam, means for holding it against rotation, a floating roller for applying stress to the warp threads, a reciprocating bar, means coacting with the reciprocating bar and floating roller for lifting the bar when the roller reaches a predetermined height and thereby temporarily release the warp beam holding means, an inclined plane and a projection carried by the reciprocating bar in position to ride up the inclined plane when the bar is lifted and thereby further raise and maintain the reciprocating bar momentarily in a raised position.

6. In a loom, a warp beam, means for applying stress to the warp threads tending to rotate the warp beam, a pawl and ratchet for holding the warp beam against rotation, a reciprocating bar, means coöperating with the bar and said stress applying means to

lift the bar, an inclined plane and a projection carried by the reciprocating bar in position to engage the inclined plane when the bar is lifted, the said inclined plane and the said projection having a yielding movement one relative to the other.

7. In a loom, a warp beam, means for applying stress to the warp threads tending to rotate the warp beam, a pawl and ratchet for holding the warp beam against rotation, a reciprocating bar, means coöperating with the bar and the stress applying means for lifting the bar, the said bar being provided with a projection in position to engage and trip the pawl when the bar reaches a predetermined height, a spring actuated inclined plane provided with a recess in its side and a projection carried by the reciprocating bar in position to ride up the inclined plane when the bar is raised and drop through the recess thereby further raising and maintaining the reciprocating bar momentarily in a raised position and then allowing it to fall.

8. In a loom, a warp beam, means for holding it against rotation, a floating roller for applying stress to the warp threads, a weight bar suspended from the floating roller, slotted guides for receiving the opposite ends of the weight bar, means under the control of the floating roller and its weight bar for temporarily releasing the warp beam and adjustable supports arranged to coact with the slotted guides for holding the weight bar temporarily in an elevated position.

9. In a loom, a warp beam, an adjustable brake band for applying friction to resist the rotation of the warp beam, a ratchet wheel fixed to rotate with the warp beam, a spring actuated pawl arranged to coöperate with the ratchet wheel and provided with a recess in its tail, a floating roller for applying stress to the warp threads, a reciprocating bar, means coöperating with the floating roller and bar for raising the bar into position to operate the pawl, the said reciprocating bar having a projection thereon adapted to move into and out of the recess in the tail of the pawl when the reciprocating bar is in its non-operative position and an inclined plane arranged to coöperate with the reciprocating bar when the latter has been raised to a predetermined height by the floating roller.

In testimony, that I claim the foregoing as my invention, I have signed my name in presence of two witnesses, this fourteenth day of December, 1911.

WILLIAM J. LUTTON.
